DESCRIPTION

U.S. PATENT DOCUMENTS

FIG. 1 is a top-rear-right perspective view of a vessel asymmetrical dock, showing the design;

FIG. 2 is a rear view of the vessel asymmetrical dock of FIG. 1;

FIG. 3 is a front view of the vessel asymmetrical dock of FIG. 1;

FIG. 4 is a right view of the vessel asymmetrical dock of FIG. 1;

FIG. 5 is a left view of the vessel asymmetrical dock of FIG. 1;

FIG. 6 is a top view of the vessel asymmetrical dock of FIG. 1; and,

FIG. 7 is a bottom view of the vessel asymmetrical dock of FIG. 1.

The broken lines in the reproductions are provided for the purposes of illustrating portions of the vessel asymmetrical dock that form no part of the claimed design.
